PHONOGRAPH CABINET

William G. Broman, Chicago, Ill., assignor to The Seeburg Corporation of Delaware, Chicago, Ill.

Filed June 25, 1970, Ser. No. 23,658

Term of patent 14 years

Int. Cl. D14—01

U.S. Cl. D56—4

FIG. 3FIG. 4FIG. 1 is a front, top and right side perspective view of a phonograph cabinet, showing my new design;

FIG. 2 is a right side elevational view;

FIG. 3 is a front elevational view; and

FIG. 4 is a top plan view thereof.

The rear and bottom, not shown, are substantially plain and unornamented.

Portions of FIGS. 1, 3 and 4 are diagonally lined to indicate transparency. The mesh fragmentarily shown in FIGS. 1 and 3 by criss-cross lines is continuous within the boundaries included.

I claim:

The ornamental design for a phonograph cabinet, substantially as shown and described.
